UNITED STATES PATENT OFFICE

GARFIELD A. WOOD, OF ALGONAC, MICHIGAN

PROPELLER CONSTRUCTION

Application filed October 11, 1930. Serial No. 487,925.

This invention relates to a propeller mounting and construction particularly adapted for use in conjunction with motor boats. It has been found, after extensive experience with outboard motor boats, that the axis of the propeller should be substantially horizontal, or if not horizontal, it should tilt slightly downward from rear to front rather than in the opposite direction, as is the case 10 with the propeller shaft running from the engine in a motor boat to the propeller wheel. Greater speed with the same horse power consumed is accomplished when the axis of the propeller wheel is substantially horizontal or inclined as stated.

With the attainment of the higher speeds of movement of motor boats the front end of the boat is lifted out of the water and the wetted surface is a comparatively small area 20 at the stern of the hull. The propeller should be so located that the consumption of power necessary for the attainment of the higher speeds shall not be unduly large and, having discovered that the location of the 25 axis of the propeller wheel has an important bearing on this subject, the present invention is concerned with the construction of a practical, simple and efficient mechanism for making a suitable universal joint connection between the driving shaft from the engine and the propeller wheel which is mounted to turn about a substantially horizontal axis; and further to provide a means whereby the axis of the propeller wheel may be 30 adjusted so that the best results can be obtained.

An understanding of the invention for the attainment of the ends stated may be had from the following description, taken in connection with the accompanying drawing, in which, Fig. 1 is a side elevation of a motor boat equipped with my invention.

Fig. 2 is a fragmentary enlarged longitudinal vertical section through the universal joint noted and the mounting for the propeller wheel, and illustrating in side elevation the means for effecting an adjustment of the axis of the propeller wheel, and,

Fig. 3 is an enlarged transverse vertical section through the joint connection between

the driving shaft and the hub of the propeller.

Like reference characters refer to like parts in the different figures of the drawing.

The hull 1 of the motor boat may be of any desired design, the driving shaft 2 from the engine to the propeller wheel extending downwardly and to the rear at an angle to the horizontal. The hull is equipped with the usual rudder 3 which is no way concerned with the present invention. At the rear end and underside of the hull in front of the rudder a strut 4 is permanently secured, extending downwardly from the hull to which, at its lower end, an arm 5 is pivotally connected at 6, as best shown in Fig. 2, having an integral bearing 7 at its lower end. The arm is extended to the rear from the point where it is pivotally connected to the strut and then turned upwardly as at 8 to lie back of the strut 4. A screw threaded rod 9 is attached at its front end to a U-shaped stirrup 10 embracing and pivotally connected to the strut 4 near its upper end and adjacent its rear edge. The rod 9 passes freely through a collar at the upper end of the extension 8 of arm 5 and nuts 11 are threaded on the rod 9, one in front and the other in back of said collar.

It is evident that by adjusting the positions of nuts 11 the arm 5 may be turned about the pivot 6 and the bearing 7 changed in position so that its axis may be substantially horizontal or, if desired, tilted downwardly from its rear to its front end to a slight degree.

The propeller wheel hub 12 has the usual propeller vanes 13 extending radially therefrom and is located at the front end of and in alignment with the bearing 7. A shaft 14 extends from the hub 12 rearwardly through the bearing 7, is threaded at its rear end and receives securing and locking nuts 15, as shown. The head 12 at its front end is recessed and is formed with a plurality of spaced apart longitudinal grooves 16 in the sides of the recess. The recess is of smaller diameter farther back in the hub and is inferiorly threaded, as indicated at 17. A thrust head 18 is screwed into the recess 17.

It has a rod 19 extending longitudinally of and through the shaft 14 and, preferably, at its rear end is squared so that a wrench may be applied thereto to adjust the head 18 to 5 any desired position in the threaded recess 17. The front side of head 18 is of concave formation, the purpose of which will later appear.

The rear end of the driving shaft 2 extends into the opening or recess in the front end 10 of the hub 12, the rear end of shaft 2 being somewhat enlarged to make an elongated cylindrical head 20 in which, at a plurality of spaced apart points around the head, somewhat elongated recesses 21 are made, one 15 opposite each of the recesses 16 and 21 opposed to each other, it being evident that the torque from the driving shaft may be readily transmitted to the propeller through the ball connection made and that the change of angle 20 which takes place when the driving shaft and propeller are rotated is fully taken care of by the construction described.

The rear end of the head 20 also has a concave semi-spherical recess therein in which a 25 ball 23 is located which, at its rear side, bears against the front concaved end of the head 18, previously described. This provides a practical thrust joint which is necessary for the proper connection of the driving shaft 2 to 30 the propeller when the axis of rotation of the propeller is at other than in alinement with the axis of the drive shaft.

The construction described has proved very practical and efficient for the purposes 35 for which it is designed and permits the relative adjustment of the propeller to its drive shaft without detriment to the driving connection between them and with a saving in power consumed, particularly at the higher 40 rates of speed.

It is to be understood that the thrust of the propeller is transmitted to the drive shaft 2 and thence by said drive shaft to a suitable bearing within the hull of the motor 45 boat, so that the entire thrust of the propeller urging the boat forward is transmitted from the head 18 through the ball 23 to the driving shaft. The ball 23 not only is amply 50 able to sustain this thrust but it also greatly lessens any friction there may be between the parts as will be obvious.

The invention is defined in the appended 55 claims and is to be considered comprehensive of all forms of structure coming within their scope.

I claim:

1. In combination with a motor boat having a hull, a strut depending from the lower side of the hull near its rear end, a substantially horizontal bearing sleeve carried at the lower end of the strut, a propeller having a hub located at the front end of the bearing sleeve and having a shaft extending from the rear side of the hub through said bearing sleeve, said hub at its front end being recessed

and having a plurality of longitudinal grooves in the sides of said recess, a driving shaft extending downwardly and to the rear from said hull at an angle to the horizontal to the recess in the hub of the propeller, the rear end portion of the driving shaft extending into said recess, said rear end portion of the driving shaft having a plurality of longitudinal grooves therein located opposite the grooves in the recess of said hub, balls disposed in the grooves of the propeller shaft and said hub, and a thrust bearing disposed between the rear end of the drive shaft and the inner end of said recess. 70 75

2. In combination with a motor boat having a hull, a strut secured to and depending from the lower side of the hull near the rear end thereof, a substantially horizontal elongated bearing sleeve carried at the lower end of the strut, a propeller having a cylindrical hub located at the front end of the sleeve, and having a shaft extending from the rear end of the hub through said sleeve, said hub of the propeller being recessed at its front end, a drive shaft extending downwardly and to the rear at an angle to the horizontal from the hull to said hub of the propeller, the rear end portion of the drive shaft being received in said recess, universal driving connections between the rear end portion of the driving shaft and said hub of the propeller, a ball located at the rear end of said driving shaft, a member threaded into the inner portion of said recess in the propeller hub against which the ball bears, and means for adjusting said member in the direction of the length of the axis of said bearing sleeve. 80 85 90 95

3. In combination with a motor boat having a hull, a strut depending from the hull at the bottom thereof and near its rear end, a substantially horizontal elongated bearing sleeve carried at the lower end of the strut, a propeller located in front of said sleeve having a hub disposed against the front end of the sleeve and a shaft of reduced diameter extending through the sleeve, nuts threaded onto the rear end of said shaft, said propeller hub having a recess at its front end and said recess being of reduced diameter at its inner portion and interiorly threaded, and said shaft having a longitudinal opening therein, a member formed with a concaved front end threaded into said threaded portion of the recess, a rod extending from said member longitudinally of and through the shaft, a driving shaft extending downwardly and to the rear from the hull at an angle to the horizontal having its rear end received within the recess of said propeller hub, universal driving connections between the rear end of the driving shaft and propeller hub within the recess and a spherical ball located 110 115 120 between the rear end of the driving shaft and said threaded bearing member and bear-

125 130

- ing against the concaved front end of the bearing member, the rear end of the driving shaft having a semi-spherical recess in which the ball is seated.
5. 4. In combination with a motor boat having a hull, a strut depending from the bottom of said hull and near the rear end thereof, an arm pivotally mounted between its ends near the lower end of the strut, an elongated sleeve bearing at the lower end of the arm adapted to be located with its axis substantially horizontal, means interposed between the opposite end of the arm and said strut for adjusting the arm and the bearing sleeve
- 10 15 carried thereby to different positions, a propeller mounted on and located in front of said bearing sleeve for rotative movement, a driving shaft extending downwardly and to the rear at an angle to the horizontal from said hull to the propeller, and driving and thrust bearing connections between the rear end of the driving shaft and said propeller.
- 20 25 5. In combination with a boat having a hull, a substantially horizontal elongated bearing sleeve located below the rear end portion of the hull, means for securing the sleeve to the hull, a propeller rotatably mounted on and carried by said sleeve, a driving shaft extending downwardly and to the rear from said hull to the propeller, universal driving connections between the rear end portion of the driving shaft and the propeller, and a thrust bearing between the rear end of the driving shaft and said propeller.
- 30 35 6. In combination with a boat having a hull, an elongated bearing sleeve located below the lower side of the hull at the rear end portion thereof, means for mounting the sleeve on said hull for adjustment, whereby the sleeve may be adjusted to locate its longitudinal axis substantially horizontal or inclined at a slight angle to the horizontal, a propeller mounted on and carried by said sleeve, a driving shaft extending downwardly and to the rear from the hull at an angle to the horizontal, universal driving connections between the rear end portion of the drive shaft and said propeller, and a thrust bearing between said propeller and the rear end of the driving shaft.
- 40 45 50 7. In combination with a boat having a hull, a strut attached to and depending from the hull at the rear end thereof, an arm pivotally mounted between its ends adjacent the lower end of the strut, an elongated bearing sleeve located substantially horizontal connected to said arm below the strut, said arm above the pivot extending to one side of and back of the strut and having a collar at its upper end, a threaded rod pivotally mounted at its front end on said strut and extending through the collar, nuts on the rod, one in front and the other back of the collar, a propeller rotatably mounted on and carried by said bearing sleeve, a driving shaft extend-

- ing downwardly and to the rear from the hull, universal driving connections between the rear end portion of the driving shaft and said propeller, a thrust bearing located between the rear end of the driving shaft and the propeller, and adjustable means for maintaining a snug engagement for said thrust bearing between the drive shaft and propeller.
- 70 75 8. In combination with a motor boat having a hull, a propeller for driving the same, a strut rigidly projecting below said hull, means attached to said strut for rotatably mounting said propeller on a rigidly maintained axis, said propeller mounting means being adjustable relative to said strut for the purpose of varying the vertical inclination of said axis relative to the hull and means for driving said propeller.
- 80 85 9. The elements in combination defined in claim 8, wherein the said means for mounting said propeller is located at the rear of said propeller.
- 90 95 10. In combination with a motor boat having a hull, a propeller for driving the same, means for mounting said propeller beneath said hull to rotate on a rigidly maintained axis, said mounting means combining means whereby the vertical inclination of the axis of the propeller relative to the hull can be altered and means for rotating said propeller, said means for rotatably mounting said propeller being located at the rear of said propeller.
- 100 105 11. In combination with a motor boat having a hull, a propeller for driving the same, means for mounting said propeller beneath said hull to rotate on a rigidly maintained axis, said mounting means combining means whereby the vertical inclination of the axis of the propeller relative to the hull can be altered and means for rotating said propeller, said means for rotatably mounting said propeller being located at the rear of said propeller and the means for driving said propeller comprising a shaft extending forwardly of said propeller.
- 110 115 120 125 130 12. In combination with a motor boat having a hull, a propeller for driving the same, means for mounting said propeller beneath said hull to rotate on a rigidly maintained axis, said mounting means combining means whereby the vertical inclination of the axis of the propeller relative to the hull can be altered, means for rotating said propeller, said means for driving said propeller comprising a shaft extending forwardly from said propeller and thrust bearing means associated with said propeller and said shaft and arranged to transfer the thrust of said propeller to said shaft.
13. The elements in combination defined in claim 8, wherein the said means for rotatably mounting said propeller is located at the rear of said propeller and the means for

driving said propeller comprises a shaft extending forwardly of said propeller.

14. The elements in combination defined in claim 8, wherein said means for driving said propeller comprises a shaft extending forwardly from said propeller and thrust bearing means associated with said propeller and said shaft and arranged to transfer the thrust of said propeller to said shaft.

10 15. In combination with a boat hull, a propeller for driving the same, bearing means for mounting said propeller to rotate on a rigidly maintained axis, adjustable means for varying the vertical inclination of the 15 axis of said propeller relative to the hull without appreciably altering the vertical position of the propeller relative to the hull, means for driving said propeller, said means for driving said propeller comprising a shaft 20 extending forwardly from said propeller, and thrust bearing means associated with said propeller and said shaft and arranged to transfer the thrust of said propeller to said shaft.

25 In testimony whereof I affix my signature.
